AMPLITUDE MODULATION

Maurice Artzt, Princeton, N. J., assignor to Radio Corporation of America, a corporation of Delaware

Application February 22, 1943, Serial No. 476,713

14 Claims. (Cl. 179—171.5)

My invention relates to the art of amplitude modulation and particularly to a method of and means for amplitude modulating an oscillator of the resistor-capacitor or RC type. The invention will be described, for the purpose of illustration, as applied to a facsimile system but it should be understood that the invention is of general application.

One of the objects of the invention is to provide a method of and means for modulating a carrier wave at the maximum modulating or keying rate that will produce a satisfactory signal at the receiver.

Another object of the invention is to provide an improved method of and means for amplitude modulating or keying a resistor-capacitor oscillator so that the keying signal itself always determines the zero-phase starting position of the carrier wave.

A further object of the invention is to provide a method of and means for keying a carrier wave at a high speed without the introduction of transient signals or direct-current components.

A still further object of the invention is to provide an improved method of and means for amplitude modulating an oscillator of the resistor-capacitor type.

A still further object of the invention is to provide an improved method of and means for amplitude modulating a sine wave oscillator by keying dots of variable length or duration.

In a preferred embodiment of the invention the oscillator is of the RC type having a feed-back circuit in which a delay network shifts the phase of the oscillation frequency signal 180 degrees. The output of the oscillator tube is fed into the delay network through a cathode-follower tube whereby the amplitude of oscillation depends upon the gain of the latter tube. The gain of the cathode-follower tube is controlled by means of a modulator tube to which the modulating signal is applied, the modulator tube anode and the cathode-follower tube anode being supplied with voltage through a common anode resistor whereby an increase in anode current in the modulator tube causes a decrease in anode voltage on the cathode-follower tube, thus reducing its gain. The cathode of the cathode-follower tube is prevented from becoming less positive with respect to ground at this time by connecting the cathode resistor of the cathode-follower tube in series with a cathode resistor of the modulator tube. If circuit values are properly selected, the decreased voltage drop across one

cathode resistor is balanced by the increased voltage drop across the other cathode resistor and the potential of the cathode-follower tube's cathode with respect to ground is not affected by the modulating signal.

Therefore, the modulating signal does not introduce any transient at the input of the delay network; it merely controls the gain in the feed-back loop, thus controlling the amplitude of the sine wave oscillation. In the facsimile application of the invention which will be described, this amplitude control takes the form of starting and stopping the oscillations. An important feature of the invention is that a keying signal starts an oscillation cycle at its zero phase position and always allows the oscillator to finish a complete oscillation cycle once the cycle has started.

In accordance with another feature of my invention the oscillator is provided with an additional feed-back connection or network having substantially the same time constant as the oscillator build up or decay whereby the oscillator may be started practically instantaneously by a keying signal with the first cycle of oscillation at full amplitude.

The invention will be better understood from the following description taken in connection with the accompanying drawings in which

Figure 1 is a circuit diagram of a simplified form of the invention; Figure 2 is a circuit diagram of one preferred embodiment of the invention; Figure 3 is a group of graphs which are referred to in explaining the invention; and Figure 4 is a circuit diagram of another embodiment of the invention. In the several figures similar parts are indicated by similar reference characters.

Referring to Fig. 1, the oscillator tube T1 may be a screen grid vacuum tube having a cathode 10, a control grid 11, a screen grid 12 and an anode 13. Cathode biasing may be provided by a resistor 14 shunted by a capacitor 16. The anode 13 is direct-current connected to the grid 17 of a cathode-follower tube T2. The tube T2 may be a triode having the grid 17, an anode 18, and a cathode 19. Anode voltage is supplied to the tubes T1 and T2 through resistors 20 and 21, respectively.

The oscillator is of the well known resistor-capacitor or RC type comprising a delay network 22 consisting of a plurality of sections of series resistors 23 and shunt resistors 24. The coupling into the network 22 is through a cathode load resistor 26. The output of the net-work 22 is fed back to the grid 11 of tube T1 through a conductor 27. The oscillator will oscillate at

the frequency for which the network 22 introduces a phase shift of 180 degrees. The oscillator output, which will be sinusoidal in wave form, may be taken off the cathode 19 through an output lead 28.

The gain of tube T2 is varied by means of a variable resistor device T3' which is connected in series with the anode resistor 21 and a resistor 31 whereby elements 21, T2 and 31 form a potentiometer across the plate voltage supply. Resistors 21 and 31 preferably have the same value of resistance, this value preferably being less than that of the load resistor 26. The value of resistor 26 should be about equal to the plate-cathode impedance of the tube T2 if the cathode 19 is to follow the grid 17 closely.

Now considering the operation of the modulating circuit, assume that the potential on the anode 13 of tube T1 (which is also the potential on the grid 17 of tube T2) is not varying, and assume that the resistance of T3' is decreased. Then the increased current flow through 21, T3' and 31 makes the anode 18 of tube T2 go less positive and makes the high end of resistor 31 go more positive with respect to ground. Thus the current flow through the tube T2 and the cathode resistor 26 decreases both because of the lowered anode-to-cathode potential and because of the tendency of the cathode 19 to go more positive with respect to the fixed potential of the grid 17.

As a result of this decreased current flow through tube T2 and resistor 26, the voltage drop across the anode-cathode impedance of tube T2 is decreased and the voltage drop across resistor 26 is decreased. At the same time the voltage drop across resistor 31 has increased. Therefore, the potential of the cathode 19 with respect to ground is unchanged by the change that was made in the resistance of T3' with the result that no transient signal is impressed upon the network 22. The gain of the tube T2 is lowered, however, because of the lowering of the anode-to-cathode voltage.

Assume now that the tube T1 is oscillating whereby a sine wave voltage is present on the anode 13 and is impressed on the grid 17 of tube T2. The potential of cathode 19 will follow the sine wave voltage on the grid 17, and the sine wave oscillation is thus impressed upon the network 22 and fed back to the grid 11 of the tube T1 in the proper phase to reinforce the oscillations. The magnitude of the oscillations will depend upon the gain of the cathode follower tube T2. Thus, if the anode-cathode voltage of T2 has been lowered by a change in T3', the sine wave variations on the grid 17 will produce current variations in resistor 26 that are of lower amplitude and less signal is fed back through network 22. The result is a reduction in amplitude of the sine wave oscillations in response to a reduction in the resistance of T3', with no introduction of transient voltages.

Fig. 2 shows a useful embodiment of the invention which differs from Fig. 1 in that the resistor T3' is a vacuum tube T3 which has its anode-cathode impedance varied by a modulating or keying signal. The grid of tube T3 is connected through an input resistor 33 to a suitable biasing potential obtained from a potentiometer comprising resistors 34 and 36. A filter capacitor 37 is connected across resistor 36. The keying signal amplitude modulates the oscillator as previously described.

In order to bring the oscillations up to full

amplitude substantially instantaneously in response to the application of a keying signal, there is provided a regenerative feed-back connection from a point on the plate resistor 21 of the tube

5 T3 to a point on the last resistor 24 of the network 22 to introduce feedback of a derivative of the keying signal. This connection comprises a capacitor 38 and a conductor 39. The time constant of this feed-back connection preferably 10 is substantially equal to the time of the oscillator build up or decay, that is, the time of one quarter cycle. Then a voltage fed back through 38-39 will build up to maximum in the same time an oscillation cycle builds up from zero to maximum amplitude. The time constant may be adjusted 15 by moving the tap 41 on resistor 24. The amount of feed-back may be adjusted by moving the tap 42 on resistor 21.

Figure 3 illustrates the advantage of my improved modulator as compared with the usual amplitude modulator. The graphs a and b show the unmodulated carrier wave and the keying signals, respectively. In the example illustrated, the keying signals are those supplied from a facsimile scanner and are of negative polarity. If 20 the signals b amplitude modulate the carrier wave a in the ordinary way, the resulting amplitude modulated signal will be as shown by the graph c, and after it passes through an A-C. 25 coupling so that the direct current component is removed it will be shown in graph d. It is 30 evident that the signal of graph d would print a medium gray almost all through this series of keying signals with only the long dot of the series printing at full amplitude.

With my invention, however, the resulting amplitude modulated signal is as shown in the graph e. While most of the short dots are slightly elongated, they are all printed at full amplitude 35 and with definite spaces between them. This results from the fact that a carrier wave cycle always builds up from zero phase at the start of a keying dot or signal and from the fact that at 40 least one full cycle of oscillation is completed regardless of when the keying signal terminates. Thus the modulated signal contains no direct-current components and can be passed through alternating-current amplifiers without obtaining 45 signal distortion of the type shown by the graph d.

Fig. 4 shows another embodiment of the invention in which a pair of diodes 51 and 52 are employed to limit the amplitude of the positive and negative cycles, respectively, of the carrier wave, the amplitude limits being controlled by 50 the tube T3 upon which the keying signals are impressed. In this circuit the output of the tube T1 is supplied directly to the delay network 22 through a conductor 53. The diode 51 is connected in series relation with the resistor 21 and with its anode connected to the conductor 53, while the diode 52 is connected in series relation with the resistor 31 and with its cathode connected to the conductor 53. As in the other 55 embodiments of the invention, the resistors 21 and 31 preferably are of equal resistance so that the application of the keying signal will change the potential at the cathode of diode 51 and the potential at the anode diode 52 like amounts, these changes being in opposite directions.

The operation is as follows, assuming that the modulating signal (graph b, Fig. 3, for example) is of negative polarity: A negative keying dot applied to the grid of T3 decreases the current flow through resistor 21, the tube T3 and the resistor 31. This causes the cathode potential of

diode 51 to go in the positive direction a certain amount and causes the anode potential of diode 52 to go in the negative direction a like amount. Thus the diodes 51 and 52 are rendered non-conducting until the amplitude of oscillation at the anode of T1 (and on conductor 53) increases enough to overcome the said cathode and anode potential changes. The amplitude increase preferably occurs in one-quarter of a cycle, after which time the diodes 51 and 52 again conduct current and load the plate circuit of tube T1 to reduce its gain and hold the amplitude to the level determined by the keying signal.

It will be noted that in Fig. 4 the keying signal will not affect the potential of the conductor 53 leading into the network 22 providing resistors 21 and 31 are equal and providing the diodes 51 and 52 are alike. Therefore, this circuit, like the ones previously described produces an amplitude modulated wave that contains no direct-current component.

It should be understood that the invention is not limited to the use of modulating signals of the type illustrated in Fig. 3 for keying the oscillator on and off. Sine wave or speech signal modulation, for example, may be applied to the oscillator.

I claim as my invention:

1. In combination, an oscillator of the type including a delay network for reversing the phase of the feed-back voltage, means for changing the amplitude of the oscillations which are fed into said network, the input terminals of said network having a certain direct-current potential component thereacross in the absence of changes in said amplitude, and means for simultaneously maintaining the direct-current potential component across the input terminals of said network substantially constant.

2. In combination, an oscillator of the type including a resistor-capacitor delay network for reversing the phase of the feed-back voltage, said network consisting of a plurality of recurring sections each consisting of a series capacitor and a shunt resistor, means for changing the amplitude of the oscillations which are fed into said network, the input terminals of said network having a certain direct-current potential component thereacross in the absence of changes in said amplitude, and means for simultaneously maintaining the direct-current potential component across the input terminals of said network substantially constant.

3. The invention according to claim 2 wherein the oscillator includes an additional feed-back connection which has a time constant that is of the order of the time period of one quarter cycle of said oscillations.

4. An oscillator of the resistor-capacitor type comprising an amplifier tube having an input circuit and an output circuit, a feed-back connected between said output circuit and said input circuit, said feed-back circuit including a delay network for reversing the phase of the feed-back voltage, the input terminals of said network having a certain direct-current potential component thereacross in the absence of changes in the amplitude of the oscillations applied thereto, and means connected between said output circuit and said delay network for controlling the gain of the circuit feeding into the delay network while simultaneously holding the direct-current potential across the input terminals of the delay network substantially constant.

5. The invention according to claim 4 wherein

the oscillator includes an additional feed-back connection which has a time constant that is of the order of the time period of one quarter cycle of said oscillations.

6. An oscillator of the resistor-capacitor type comprising an amplifier tube having an input circuit and an output circuit, a feed-back circuit connected between said output circuit and said input circuit, said feed-back circuit including a delay network for reversing the phase of the feed-back voltage, and means connected between said output circuit and said delay network for controlling the gain of the circuit feeding into the delay network, said last means including a second amplifier tube having an input circuit to which a modulating signal may be applied, and means including anode and cathode resistors for said second amplifier tube for balancing out the modulating signal at the input terminals of the delay network.

7. The invention according to claim 6 wherein an additional feed-back connection is provided between said anode resistor and the output end of said delay network and which has a time constant of the order of the build-up time of the oscillations generated by the oscillator.

8. An oscillator of the resistor-capacitor type comprising an amplifier tube having an input circuit and an output circuit, a feed-back circuit connected between said output circuit and said input circuit, said feed-back circuit including a delay network for reversing the phase of the feed-back voltage and also including an amplitude control amplifier through which the oscillations are fed from said output circuit to said delay network, the input terminals of said network having a certain direct-current potential component thereacross in the absence of changes in the amplitude of the oscillations applied thereto, and means for controlling the gain of said amplitude control amplifier in accordance with a modulating signal while simultaneously holding the direct-current potential across the input terminals of the delay network substantially constant.

9. The invention according to claim 8 wherein the oscillator includes an additional feed-back connection which has a time constant that is of the order of the time period of one quarter cycle of said oscillations.

10. An oscillator of the resistor-capacitor type comprising an amplifier tube having an input circuit and an output circuit, a feed-back circuit connected between said output circuit and said input circuit, said feed-back circuit including a delay network for reversing the phase of the feed-back voltage and also including a cathode coupled amplifier tube which has a cathode resistor coupled to the input terminals of said network, the input terminals of said network having a certain direct-current potential component thereacross in the absence of changes in the amplitude of the oscillations applied thereto, and means for controlling the gain of said cathode coupled tube in accordance with a modulating signal while simultaneously holding the direct-current potential across the input terminals of the delay network substantially constant, said last means comprising an amplifier tube having a cathode resistor connected in series with said first cathode resistor and with said series connected cathode resistors connected across the input terminals of said network, and a common anode resistor through which operating voltage is supplied to the anodes of said tubes, said modu-

lating signal being applied to the input circuit of said last amplifier tube.

11. The invention according to claim 10 wherein the oscillator includes an additional feed-back connection which has a time constant that is of the order of the time period of one quarter cycle of said oscillations.

12. An oscillator of the resistor-capacitor type comprising an amplifier tube having an input circuit and an output circuit, a feed-back circuit connected between said output circuit and said input circuit, said feed-back circuit including a delay network for reversing the phase of the feed-back voltage and also including a cathode coupled amplifier tube which has a cathode resistor coupled to the input terminals of said network, the input terminals of said network having a certain direct-current potential component thereacross in the absence of changes in the amplitude of the oscillations applied thereto, and means for controlling the gain of said cathode coupled tube in accordance with a modulating signal while simultaneously holding the direct-current potential across the input terminals of the delay network substantially constant, said last means comprising an amplifier tube having a cathode resistor connected in series with said first cathode resistor and with said series connected resistors connected across the input terminals of said network, and a common anode resistor through which operating voltage is supplied to the anodes of said tubes, said modulating signal being applied to the input circuit of said last amplifier tube, said anode resistor and the cathode resistor of said last amplifier tube having approximately the same resistance value

and having a value substantially less than that of the other cathode resistor.

13. The invention according to claim 12 wherein the oscillator includes an additional feed-back connection which has a time constant substantially equal to the oscillation build-up time of the oscillator and wherein the said modulating signal consists of keying dots of variable width for starting and stopping said oscillations.

14. An oscillator of the resistor-capacitor type comprising an oscillator tube having an input circuit and an output circuit, a feed-back circuit connected between said output circuit and said input circuit, said feed-back circuit including a delay network for reversing the phase of the feed-back voltage, an oscillation control amplifier tube which has an anode resistor and a cathode resistor, said two resistors having approximately the same resistance, the input terminals of said network having a certain direct-current potential component thereacross in the absence of changes in the amplitude of the oscillations applied thereto, and means for controlling the gain of said control tube in accordance with a modulating signal while simultaneously holding the direct-current potential across the input terminals of the delay network substantially constant, said last means comprising a rectifier connected between the anode of said oscillator tube and the anode of said control tube to conduct current in one direction, and a second rectifier connected between the anode of said oscillator tube and the cathode of said control tube to conduct current in the opposite direction.

MAURICE ARTZT.
